US00D976955S

(12) **United States Design Patent** (10) **Patent No.:** **US D976,955 S**
Witchell (45) **Date of Patent:** **** Jan. 31, 2023**

- (54) **DISPLAY PANEL WITH A COMPUTER GENERATED ICON**
- (71) Applicant: **SIGNIFY HOLDING B.V.**, Eindhoven (NL)
- (72) Inventor: **Dan Witchell**, London (GB)
- (73) Assignee: **Signify Holding B.V.**, Eindhoven (NL)
- (**) Term: **15 Years**
- (21) Appl. No.: **29/752,933**
- (22) Filed: **Sep. 29, 2020**

Related U.S. Application Data

- (63) Continuation-in-part of application No. 29/662,181, filed on Sep. 4, 2018, now abandoned.

(30) **Foreign Application Priority Data**

Mar. 1, 2018 (EM) 004733418-0004

(51) **LOC (14) Cl.** **14-04**

(52) **U.S. Cl.**

USPC **D14/490**; D14/489

(58) **Field of Classification Search**

USPC D14/485-495

CPC . G06F 3/04845; G06F 3/04847; G06F 1/1692

See application file for complete search history.

Primary Examiner — Daniel J Domino

(57) **CLAIM**

The ornamental design for a display panel with a computer generated icon, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display panel with a computer generated icon showing my design.

The broken lines in the drawings depict parts of the ornamental design that form no part of the claimed design.
